WALTER I. RESNIKOFF, OF NEW YORK, N. Y.

EXIT-DOOR CONTROL.

1,112,323.

Specification of Letters Patent. Patented Sept. 29, 1914.

Application filed March 18, 1914. Serial No. 825,648.

To all whom it may concern:

Be it known that I, WALTER I. RESNIKOFF, a citizen of the United States, and a resident of the city of New York, borough 5 of Brooklyn, in the county of Kings and State of New York, have invented a new and Improved Exit-Door Control, of which the following is a full, clear, and exact description.

10 My invention relates to means for automatically unlocking exit doors, and has reference more particularly to doors leading to fire-escapes.

The fire ordinance for factories requires 15 a manufacturer to maintain the factory doors leading to fire-escapes unlocked, and the unobservance of the rule is punished by heavy fines and imprisonment. It is necessary to lock the doors every night to prevent 20 theft; and very often by inadvertence the doors remain locked during the morning of the working day; thus, the rules of the fire ordinance are broken unintentionally and no excuse can be pleaded.

25 To obviate the above objections, I have devised a door structure which is normally locked, which automatically unlocks when the same is approached from the interior side, in which the means for unlocking the 30 door remain inoperative as long as the door remains open, and automatically becomes operative as soon as the door is closed.

The object of the invention is to provide 35 a simple, strong, and inexpensive device for automatically unlocking the door, which has few movable parts apt to get out of order, and which is automatic in its action.

I obtain the above object by the diagrammatic representation of the device illustrated 40 in the accompanying drawing forming a part of the specification, in which similar characters of reference indicate corresponding parts in all the views and where-
in—

45 Figure 1 is a longitudinal section through a door structure embodying my invention showing the door closed; Fig. 2 is a similar section showing the door open; and Fig. 3 is a horizontal, transverse section on line 50 3—3, Fig. 1.

55 Referring to the drawings, 4 represents an exit-door opening exteriorly and leading from the building to a fire-escape 5. The door preferably carries a bracket 6 which is adapted to be engaged by a door-locking bolt 7 mounted to slide alongside the frame

and guided in its movement at its upper end adjacent the bracket 6 by a bracket 8 secured to the door frame. The bolt at its lower end is pivotally secured to a pedal 9 adjacent its free side. The other side of the pedal is hinged to the floor 10. The free end of the pedal is raised from the floor by a pair of resilient members 11 secured to the floor, whereby the bolt 7 is maintained in engagement with the bracket 6 of the door, thereby locking the door (see Fig. 1). When a person steps on the pedal 9, the free end of the same is depressed, carrying therewith the door bolt 7, which disengages the bracket 6 of the door, leaving the door free to move outwardly toward the fire-escape 5. The door, if desired, may be provided with spring hinges normally tending to force the door open.

To prevent the bolt 7 from regaining its locking position when the door is open, catches 12 are provided to retain the pedal in the depressed position. The catches 12 are pivotally connected, on a common pivot 12', suitably secured to the floor 10 under the pedal 9. The pedal 9 is provided with apertures 13 through which said catches are adapted to project when the same is depressed by the weight of the person standing thereon. A spring 14 tends to move the catches 12 so that they will engage the pedal and prevent the raising of the same under the action of the springs 11. A slide 15 is positioned between the door 4 and one of the catches 12, so that when the door 4 is opened by the displacement of the pedal 9 under the weight of a person, the spring 14 moves the catches into operative position and retains the depressed pedal. The spring 15 will also move the slide 15 from the position shown in Fig. 1 to the position shown in Fig. 2 and, therefore, the pedal 9 will remain in the depressed or inoperative position as long as the door 4 is open. But when the door 4 is moved into closed position, it will engage in its closing movement the slide 15 and force the catches 12 to disengage the pedal 9, thus releasing the pedal, which will move the bolt 7 into engagement with the bracket 6 of the door and thereby lock the door. It is understood that the resiliency of the springs 11 which carry the pedal 9 are so adjusted as to give under a proper weight.

It will be noted that by means of the device disclosed herein, the door, being opened

by a person passing therethrough, will remain open unless closed by the same person. This is of great importance in case of a fire, as the door will unlock as soon as a person has stepped on the pedal 9 and the door can then be opened by the person standing on the pedal, and the door will remain open until the door is purposely closed. It may be further remarked that 10 the device for unlocking the door is only operable from the inner side, no portion of the mechanism being operable from the outside of the building, thus the device is burglar-proof.

15 The operation of the door is as follows: A person approaching the door interiorly must step on the pedal 9 to reach the door, thus causing a downward movement of the pedal 9, which movement of the pedal disengages the bolt 7 from the bracket 6 carried by the door, whereby the door is unlocked and can be opened by the person standing on the pedal. The downward movement of the pedal and the opening of 20 the door will permit the spring 14 to force the catch 12 in engagement with the pedal, thus the bolt 7 is prevented from returning to its normal position until the door 4 is moved back to its closed position. When 25 the door 4 is moved to its closed position it will engage the slide 15, which will disengage the catch 12 from the pedal 9, thus releasing the pedal, which, under the action of the springs 11, will move the bolt 7 into 30 engagement with the bracket 6 and lock the door again.

Having thus described my invention, I claim as new and desire to secure by Letters Patent:

40 1. In an exit-door control, a door adapted to open exteriorly; a pedal mounted to swing to and from the floor on the inner side of the door; a door bolt carried by the free end of the pedal; means for guiding 45 the bolt on the door frame; resilient means normally raising the free end of the pedal from the floor whereby the bolt engages the door, said free end of the pedal being adapt-

ed to move toward the floor when a predetermined weight is placed thereon, thus disengaging the bolt from the door; means adapted to project through and engage the pedal when the free end thereof is depressed toward the floor and the door is open, and retain said pedal in said depressed position; 55 and means positioned intermediate said first mentioned means and the door whereby when said door is closed said first mentioned means release the pedal, thus raising the free end of the pedal from the floor and locking the door by means of the bolt.

2. In an exit-door control, a door adapted to be opened exteriorly; a pedal pivotally connected with one side to the floor, the side free to move being adjacent the door; a bolt pivotally connected to the pedal adjacent the side free to move; means for guiding the bolt on the door frame; means carried by the door adapted to be engaged by said bolt; resilient means normally raising the free 70 side of the pedal whereby the bolt locks the door, the movable side of the pedal adapted to be depressed to the floor by a predetermined weight placed on the pedal whereby the bolt unlocks the door, said pedal having apertures therein; catches carried by the floor adapted to project through said apertures when the pedal is depressed; a resilient member associated with the catches and normally tending to force said catches 75 into engagement with said pedal when the same is depressed; and a slide positioned intermediate the door and said catches, said slide being movable by the spring engaging the catches when the door is open 80 and, by the door when the same is moved to the closing position, substantially as and for the purpose set forth.

In testimony whereof I have signed my name to this specification in the presence of 90 two subscribing witnesses.

WALTER I. RESNIKOFF.
